BURNISHING MACHINE

Edwin W. Smith, Beverly, Mass., assignor to
United Shoe Machinery Corporation, Flemington, N. J., a corporation of New Jersey

Original application July 1, 1941, Serial No.
400,608. Divided and this application January
21, 1943, Serial No. 473,053

4 Claims. (Cl. 12—78)

This invention relates to burnishing machines and is illustrated herein as embodied in tool supporting mechanism adapted for use in an edge setting machine of the type disclosed in an application for United States Letters Patent Serial No. 400,608 filed July 1, 1941, in my name and of which the present application is a division. The above mentioned application Serial No. 400,608 is a continuance of an application for United States Letters Patent Serial No. 335,756 filed May 17, 1940, in the names of Laurence E. Topham and Edwin W. Smith, and upon which was granted, on May 19, 1942, Letters Patent No. 2,283,239.

In machines of the type under consideration the tool holder is oscillated at a high speed about a horizontal axis and has a pair of cylindrical openings which are inclined at somewhat less than 90° to said axis. In each of these openings is slidably and rotatably mounted the cylindrical spindle of a tool carrier having secured to it an associated edge setting tool. The carriers are normally moved to outward positions away from the axis of oscillation of the tool holders by springs operating against the inner ends of the associated carrier spindles. Provision is usually made for yieldably resisting the turning of the spindles in the cylindrical openings under pressure of the work.

It is an object of the present invention to provide an improved means for limiting the movement of the tool carriers away from the axis of oscillation and also for yieldably resisting said turning movement. In accordance with this object, a feature of the invention consists in the provision of a resilient member engageable with a flat bottom of a groove formed in the side of each of the carrier spindles for yieldably resisting rotation of the tool carriers from their neutral positions in the openings in the tool holders and for limiting outward movement of the carriers in their respective openings.

The various features of the invention will be understood and appreciated from the following detailed description read in conjunction with the accompanying drawing, in which

Fig. 1 is an angular view, partly broken away, of the operating head of the illustrative machine; and

Fig. 2 is a vertical longitudinal section, partly broken away, of the head of the machine.

In the illustrative construction there is shown a shaft 20 (Fig. 1) which is rotatably mounted in a bearing 22 and is oscillated or vibrated back and forth at a high rate of speed by driving

mechanism of the type illustrated in United States Letters Patent No. 2,190,810, granted February 29, 1940, on an application filed in the name of L. E. Topham. Slidably and rotatably mounted in the shaft 20 is a spindle 24 which projects rearwardly from a holder 26, the holder being urged in a direction indicated by reference numeral 28 lengthwise of the axis 30 of the shaft by a spring 32 which is mounted in a cylindrical opening in the spindle.

The oscillating shaft 20 is provided with a comparatively large head 34 having a pair of oppositely disposed notches 36 (Fig. 1) which form part of the driving connection that causes the holder 26 to move in unison with the oscillating shaft 20. The remainder of the driving connection is formed by a pair of lugs 38 of the holder which are held in the notches 36 by the action of the spring 32. Attached to and forming part of the head 34 are a pair of oppositely inclined arcuate plates 40 which extend obliquely to the direction of oscillation of the shaft 20, the plates being so located that their ends form the side walls of the notches 36. The plates 40 are attached to the head 34 by screws 42 and form runways down which the lugs 38 ride when the tools are shifted 180° about the axis 30 upon thrusting a hand lever 44 rearwardly through mechanism which is described in said Letters Patent No. 2,283,239.

The holder 26 has a pair of bosses 46 each having a cylindrical opening or hole 48 shaped and arranged to receive a spindle 50 of a tool carrier 52. The carrier spindles 50 are slidably and rotatably mounted in the cylindrical openings 48 and are therefore capable of rotary movement about and translatory movement along the axes of the cylindrical openings. The carrier spindles also have flat surfaces 54 formed in their inner ends and enlarged heads 56 formed in their outer tool-engaging ends. A burnishing tool 58 is clamped between a shoulder 60 and a plate 62, the shoulder 60 extending from the carrier head 56 and the plate 62 having a rib 66 which bears against a side of the carrier head 56 and serves as a fulcrum. A clamping screw 64 binds the tool 58 between the shoulder 60 and the plate 62.

The tool carrier spindles 50 are permitted a limited amount of rotative and axial movement in the holes or openings 48, which movement allows them to follow changes in the curvature according to the sole edge. Inward movement of the spindles resulting from the pressure of the work is resisted by balls 68 carried by the inner ends

of springs 10, the balls being located beyond the inner ends of the tool carrier spindles 50 and being urged in an outward direction by the springs. Rotation of the tool carrier spindles 50 is resisted by the lower ends of a pair of depending arms or flanges 72 which extend from a light plate 74 of spring material and engage the flat surfaces 54 formed on the spindles. The flanges 72 also engage shoulders 75 on the spindles 50 at the inner ends of the flat surfaces 54 to limit outward movement of the spindles under the influence of the springs 10. The plate 74 extends transversely to the arms 72 and is provided at its opposite ends with openings which fit around the ends of posts 16, which also serve as mounting means for the springs. By using the light plate 74 of spring material and locating it centrally of the head of the tool holder 26, the relatively heavy eccentric spring-pressed latches, which have heretofore been used yieldingly to resist rotation of the tool carriers and spindles, have been eliminated, thereby reducing the inertia of the tool holder and the vibrations caused by the frequent reversals in the direction of its motion.

Having described my invention, what I claim as new and desire to secure by Letters Patent of the United States is:

1. In a burnishing machine, an oscillating holder comprising a head having tool receiving recesses therein, tool carriers slidably and rotatably mounted in said recesses, and a resilient member located centrally of said holder head and arranged resiliently to resist rotation of the tool carriers in said recesses and to limit axial movement thereof in said recesses.

2. In a burnishing machine, an oscillating tool holder having a head provided with oppositely disposed tool receiving recesses, tool carriers which are slidably and rotatably mounted in said recesses and having flat surfaces, and a resilient member located centrally of the tool holder head, said member having a pair of depending arms arranged respectively to engage the flat surfaces on the tool carriers and resiliently to resist rotation of the carriers in said recesses and also to limit axial movement of the carriers in the recesses.

3. In a burnishing machine, an oscillating holder comprising a head having a pair of oppositely disposed radial holes, tool carriers slidably and rotatably mounted in said holes, each of the carriers having a flat surface thereon located near its inner end, and a light resilient member fastened to said head centrally thereof, said resilient member having projecting arms arranged to engage the flat surfaces on the carriers and to resist rotation and axial movement thereof in said holes.

4. In a burnishing machine, a driven oscillatory head, a plurality of tool carriers each connected to said head for translatory movement along and rotary movement about an axis and each having a substantially flat surface terminating at a shoulder, and a light plate of spring material secured centrally to said head and having flanges engageable with said flat surfaces to resist said rotary movement of the carriers and with said shoulders to limit said translatory movement of the carriers.

EDWIN W. SMITH.
